[57] **CLAIM**

The ornamental design for a bottle, as shown and described.

DESCRIPTION

FIG. 1 is a perspective view of a bottle embodying my new design, with a finish depicted in phantom;

FIG. 2 is a front elevational view of the bottle of FIG. 1;

FIG. 3 is a side elevational view thereof, the side opposite being a mirror image thereof;

FIG. 4 is a back elevational view of the bottle opposite the view of FIG. 2;

FIG. 5 is a top plan view of said bottle;

FIG. 6 is a bottom view thereof;

FIG. 7 is a front elevational view of an alternative embodiment of my new design;

FIG. 8 is a side elevational view of the bottle of FIG. 7;

FIG. 9 is a back elevational view of the bottle opposite the view of FIG. 7.

FIG. 10 is a top plan view of the bottle of FIG. 7;

FIG. 11 is a bottom view thereof; and,

FIG. 12 is a perspective view thereof.

The broken lines showing a bottle neck are for illustrative purposes only and do not form part of the claimed design.
